UNITED STATES PATENT OFFICE.

EMANUEL RAWSON, OF JERSEY CITY, NEW JERSEY, ASSIGNOR TO THE SUPERHEATER COMPANY, OF NEW YORK, N. Y.

EXHAUST-STEAM INJECTOR.

Application filed January 28, 1926. Serial No. 84,472.

The present invention relates to exhaust steam injectors and has particular reference to the type disclosed in U. S. Patent No. 1,342,128, granted June 1, 1920 to J. Metcalfe, et al., as adapted to be operated by a remote control system, such as that disclosed in U. S. Patent No. 1,581,004, granted March 24th, 1925 to M. Hard, et al.

In this type of injector installation as applied to locomotives, the injector may be operated either by exhaust or live steam, as engine conditions dictate, and the several steam supply conduits leading to the injector are controlled by fluid actuated valves which are in turn controlled from the cab by the engineer. In order to secure proper control of the injector, it is necessary that the exhaust steam inlet be valved so that it may be closed at the will of the operator, and it is furthermore necessary that this valve should close against a positive pressure within the injector, in order to prevent the passage of live steam into the exhaust steam conduit when the injector is being operated wholly by live steam.

A number of valves have heretofore been suggested for this purpose, but because of the widely varying steam conditions on both sides of the valve under different injector operating conditions, the operation of the prior valves has been unsatisfactory.

The principal object of the present invention is therefore the provision of an improved form of exhaust steam valve, which may be remotely controlled, which will effectively close the exhaust steam conduit against a live steam pressure within the injector, and which will operate smoothly and efficiently under all steam conditions which may exist within the injector. Further and more detailed objects of the invention will appear as the following description, which is to be taken in conjunction with the accompanying drawings, proceeds.

In the drawings, Fig. 1 is a vertical section taken through the center line of an injector of the type hereinbefore referred to, to which a valve embodying the invention has been applied. Fig. 2 is a fragmentary section similar to Fig. 1, showing a modification of the valve illustrated in Fig. 1. Fig. 3 is a view similar to Fig. 2, showing another modification of the invention, and Fig. 4 is a section taken on the line 4—4 of Fig. 3. Fig. 5 is a fragmentary view

similar to Fig. 1, showing another form of valve applied to the injector, and Fig. 6 is a section taken on the line 6—6 of Fig. 5. Fig. 7 is a fragmentary section on a larger scale taken along the line 7—7 of Fig. 6, and Fig. 8 is a transverse section also on a larger scale taken along the line 8—8 of Fig. 6.

Referring now to Fig. 1, the injector comprises a main housing or casing formed by two sections designated as 1 and 2, in which there are serially mounted the exhaust steam cone or nozzle 3, the water cone 4, the secondary exhaust steam mixing nozzle 5, the combining tube 6 and the delivery nozzle 7, which discharges by way of the passage 8 and check valve 9 into the pipe 10 leading to the boiler check valve. Inasmuch as this portion of the apparatus is a known form, it is not believed necessary to describe it in any further detail.

As is usual in this type of injector, the housing 1 is extended and enlarged beyond the inlet end of nozzle 3 to form a steam chamber 11, to which is delivered either exhaust or live steam, depending upon the injector operating conditions, for supplying the steam nozzle 3. Exhaust steam is supplied to the injector by a conduit (not shown) through the inlet 12 formed at the end of the housing 1, and live steam at reduced pressure, hereinafter called "auxiliary" steam, is admitted to the chamber 11 by way of ports 13, which places the chamber 11 in communication with a steam passage 14 leading to the exterior of the injector housing, as may be more clearly seen in Fig. 6. The auxiliary steam passage 14 is in communication by way of port 15 with any suitable source of live steam supply which may be remotely controlled through a mechanism such as that described in Patent No. 1,581,004, hereinbefore referred to. High pressure live steam, hereinafter referred to as "supplemental" steam, is supplied by suitably controlled means, not shown, to the supplemental steam nozzle 16 by way of the passage 17 and port 18.

It will be apparent that in injectors of this type, wherein two different supplies of low pressure steam may be alternatively used, control means must be provided in the exhaust steam inlet to the injector, not only for the purpose of shutting down the latter when desired, but also to prevent the passage of auxiliary live steam into the exhaust

steam conduit leading to the injector during periods when no exhaust steam is available and the injector is being run on live steam. The present invention provides such control means in the form of a fluid actuated valve of novel construction, which is substantially balanced in either closed or open position, regardless of the steam conditions existing in the injector. As shown in Fig. 1, the exhaust steam inlet 12 is in communication with the steam chamber 11 by way of a cylindrical extension 19 of the latter, and in this extension there is slidably mounted a hollow sleeve valve 20 between which and the injector casing 1, a steam-tight joint is maintained by means of suitable packing rings 21. The internal webbing of the injector housing, which forms the steam passages 14 and 17 and a support 15 for the nozzle 16, is extended to form an open-ended sleeve 22 centrally aligned with the exhaust steam inlet 12. The sleeve 22 is internally threaded to receive an annular valve seat member 23, having a face 24 against which the end face of valve 21 seats when the latter is in closed position. The valve 20 is provided with radially extending arms 25 which support centrally of the valve a stem 26, to the end of which is secured a piston 27 slidably mounted within the central annular portion of the member 23. The latter is provided with an annular face 28, which serves not only as a stop limiting the open position of valve 20, but which, when the valve is in open position, forms with the piston 27 a steam-tight joint closing one end of the cylinder formed by the central portion of the member 23. The other end of this cylinder is formed by the plug 29, and a passage 30 cored out of the supporting web formed in the injector housing connects the cylinder with conduit 31 leading from a suitably controlled source of fluid pressure. A helical spring 32, resting at one end against the arms 25 of valve 20 and at the other end held by the annular backing ring 33, which is suitably secured in the injector housing, serves to hold the valve 20 normally in closed position, as indicated in Fig. 1. When desired, valve 20 is opened by means of fluid under pressure admitted through conduit 31 and passage 30 and acting on piston 27 to move the latter, and with it valve 20, to the right. In order to reduce the friction incident to moving the valve and also the number of parts, piston 27 is not provided with packing rings, but leakage past the piston when the latter is held in open position by fluid pressure, is prevented by the piston 27 seating against the annular face 28.

With the valve in the position shown in Fig. 1, communication between the steam chamber 11 and exhaust steam inlet 12 is cut off and the injector may be run by aux-

iliary live steam admitted through the steam passage 14. It is to be noted that under these conditions, the live steam filling the chamber 11 exerts no pressure tending to open or close valve 20, this feature being of importance, as a comparatively light spring is sufficient to keep the valve in closed position. Because of the light spring which it is possible to use with this construction, the operating piston 27 and its cylinder may be comparatively small and it is possible to locate them in the most advantageous position directly within the injector without unduly restricting the steam passage therethrough. Moreover, when exhaust steam is admitted through the inlet 12 with the valve in closed position, the steam pressure exerted on the valve is substantially balanced and this condition continues even after the valve is opened. This condition of substantial balance also holds true regardless of the presence or absence of live steam in the chamber 11, so that under all operating conditions the force tending to close the valve is substantially the same—that is, the force exerted by the spring 32. Due to the uniformity of force required to be overcome by piston 27, the action of the valve in opening and closing is even and smooth, and the shocks due to the sudden application of unbalanced forces tending to throw the valve violently to either closed or open position and resulting in strains and damage to the valve mechanism are avoided. As will also be apparent from the figure, this valve construction also permits of large and comparatively unobstructed steam passages connecting the exhaust steam inlet 12 with the chamber 11.

In Fig. 2 there is illustrated a second form of valve, in which the general construction is similar to that just described but in which the spring arrangement for closing the valve has been slightly modified. In this form the sleeve portion of the valve 20^a is spaced from the injector housing 1 and a shoulder 20^b is provided on the valve, serving as a stop for one end of the spring 32, which is located in the annular space between the sleeve portion of the valve and the injector housing. As in the form previously described, the other end of the spring is held by a backing ring 33^a fixed in the injector housing, but in this case the backing ring is formed with an integrally extending sleeve portion 33^b adapted to slidably engage the inner surface of the sleeve portion of the valve. Suitable packing rings 21^a are mounted in the portion 33^b of the backing ring and serve to form a steam-tight joint between the latter and the valve so that when the valve is in closed position, the exhaust steam inlet 12 is effectively closed. As will be readily apparent from the figure this valve construction is essentially the

same as that shown in Fig. 1, but the spring deposit of impurities carried by the exhaust arrangement in this form is such that sediment and other foreign matter, which may be carried into the injector with the exhaust steam, is prevented from fouling the spring and is less likely to hinder the free operation of the valve by accumulating on the spring or the surfaces along which the valve moves.

Figs. 3 and 4 illustrate a third form of valve of the present invention. In this form 100 a valve, placed transversely of the injector housing, a valve seat member 42 is secured to the housing. In this form a cylindrical web 34 is aligned with the exhaust steam inlet 12 and extends downwardly through the injector housing from the top thereof and is provided with a port 35 near the bottom of the injector, the latter placing the exhaust steam inlet 12 in communication with the interior of the cylindrical web. A pair of ports 36 located above the level of port 35, serve to provide communication between the interior of the web and the steam chamber 11. Between the upper level of port 35 and the lower level of port 36, the web 34 is extended inwardly to form an annular valve seat 37, against which a sleeve valve 20^b, carrying suitable packing rings in its upper portion, is seated by means of spring 32^b, the latter being retained in position by the suitably secured cover plate 38 which serves to close the top of the cylinder formed by the web 34. The valve 20^b is provided with radially extending arms which serve to support a piston 27^b, the latter being mounted in a suitable cylinder 39 secured in the bottom of the injector housing. The latter is cast with an outwardly extending web 40 surrounding the open end of cylinder 39 and the opening provided in the connection with the forms of valve already described to allow the insertion of the cylinder 39. A suitable conduit 31^b is connected to this steam chamber to supply fluid for actuating piston 27^b. In the figure securing ring for attachment to the injector housing, the valve 20^b is shown in closed position and housing, a spring backing ring and a bearing 54 bearing against the backing ring 52 and balanced except for the force exerted by the valve 46 serves to retain the latter normally in closed position.

In this form of valve the desirable feature is provided between the inlet 12 and the chamber 11 by way of ports 35 and 36, which have ample steam passages through the valve when in open position, and in addition the resistance to movement of the valve has been reduced by the cylinder 39 is provided, as in the previously described forms, with a suitable annular seat at its upper end with which the piston 27^b contacts to form a stop for the valve in the open position and a steam-tight joint preventing leakage of the operating fluid from the cylinder.

With the form of valve just described, the valve spring and the cylinder in which the valve operates are above and out of the line of flow of the exhaust steam into the injector, and are therefore not subject to the

The extension of stem 48 on both sides of

the arms 47 enables the valve to be substantially supported at two points, and as will readily be apparent, this additional support may be provided in the valve forms shown 5 in the preceding figures.

It will be obvious from the foregoing description that the present invention may be embodied in many different forms, and it is to be understood that the forms herein shown 10 and described are to be taken as illustrative and not limiting in sense, and that many variations and modifications may be made within the scope of the invention as defined in the appended claims.

15 What I claim is:

1. In an exhaust steam injector, an exhaust steam nozzle, a chamber communicating therewith having inlets supplying exhaust and live steam thereto, and a valve 20 located in said chamber intermediate said inlets for closing communication there-between, said valve being substantially free in all positions from unbalanced pressure exerted by steam from either of said inlets.

2. In an exhaust steam injector, an exhaust steam nozzle, a chamber communicating therewith having inlets supplying exhaust and live steam thereto, a valve located in said chamber intermediate said inlets for 30 closing communication there-between, resilient means acting to close said valve and fluid pressure actuated means for opening said valve against said first named means, said valve being substantially free in all positions from unbalanced pressure exerted by steam from either of said inlets, whereby said opening is resisted only by said resilient means.

3. In an exhaust steam injector, an exhaust steam nozzle, a chamber communicating therewith having inlets supplying exhaust and live steam to said chamber, a valve located in said chamber intermediate said inlets for closing communication there-between, said valve being substantially free in all positions from unbalanced pressure exerted by steam from either of said inlets, a spring acting to close said valve, and a fluid pressure actuated piston for opening 50 said valve against said spring.

4. In an exhaust steam injector, a housing forming a steam chamber having live and exhaust steam inlets, an annular valve seat mounted in said chamber intermediate said inlets, a sleeve valve mounted in said chamber and having an end face engaging said seat to close said exhaust steam inlet, resilient means acting to close said valve, and fluid pressure means for opening it.

60 5. In an exhaust steam injector, the combination with a housing forming a steam chamber having live and exhaust steam inlets and carrying an annular valve seat and a cylinder arranged concentrically of said seat; of a sleeve valve having an end face engaging

said seat to close said exhaust steam inlet, a piston mounted on said valve in alignment therewith and disposed in said cylinder, a spring acting to close said valve, and means for supplying fluid pressure to said cylinder 70 to actuate said piston and valve.

6. In an exhaust steam injector, the combination with a housing forming a steam chamber having live and exhaust steam inlets and carrying an annular valve seat and a cylinder arranged concentrically of said seat; of a sleeve valve having an end face engaging said seat to close said exhaust steam inlet, a piston mounted on said valve in alignment therewith and disposed in said cylinder, a 80 valve seat within said cylinder at one end thereof, and a face on said piston engaging said last named seat when said valve is in fully opened position.

7. In an exhaust steam injector, the combination with a housing forming a steam chamber and having an exhaust steam inlet therein; of an annular valve seat mounted in said housing transversely of said inlet and concentric therewith, a sleeve valve slidably 90 engaging said housing and having an end face engaging said seat to close said inlet, a helical spring mounted within said valve sleeve and acting to close said valve, and fluid pressure actuated means for opening 95 said valve against said spring.

8. In an exhaust steam injector, the combination with a housing forming a steam chamber having an exhaust steam inlet surrounded by an annular recess, of an annular 100 valve seat mounted in said housing transversely of said inlet and concentric therewith, a sleeve valve slidably mounted in said recess and having an end face engaging said seat to close said inlet, a spring located in 105 said recess acting to close said valve, and fluid pressure means for opening said valve against said spring.

9. In an exhaust steam injector, the combination with a housing forming a steam 110 chamber and having an exhaust steam inlet therein, of an annular valve seat mounted in said housing adjacent said inlet, a sleeve valve slidably mounted in said housing and having an end face engaging said seat to 115 close said inlet, said valve being constructed and arranged so that steam entering said chamber from said inlet flows through said valve, resilient means acting to close said valve, and fluid pressure means for opening 120 said valve against said first named means.

10. In an exhaust steam injector, the combination with a housing forming a steam chamber and having an exhaust steam inlet 125 therein, of a sleeve valve mounted transversely of said housing and acting to close said inlet, resilient means acting to close said valve, and fluid pressure means for opening said valve against said first named means, said valve being constructed and arranged 130

so that when in open position it lies outside the path of steam flow from said inlet to said chamber.

11. In an exhaust injector, a housing forming a steam chamber having exhaust and live steam inlets, a cylindrical web extending transversely of said housing and having ports therein affording the sole communication between said inlets, an annular valve seat formed in said web between said ports, a sleeve valve slidably mounted within said web and having an end face engaging said seat to close communication between said ports, a spring mounted within said web for closing said valve, said valve and spring being removable from said housing through said web, and fluid pressure actuated means for opening said valve.
12. In an exhaust steam injector, the combination with a housing having an exhaust steam inlet, of a pair of annular valve seats mounted within said housing adjacent to said inlet, a double-seated sleeve valve slidably mounted within said housing and engaging said seats to close said inlet, resilient means acting to close said valve, and fluid pressure actuated mean for opening said valve.

13. In an exhaust steam injector, the combination with a housing having a cylindrical extension terminating in an exhaust steam inlet; of a valve seat member mounted in said housing, said member comprising a pair

of spaced annular valve seats located transversely of and concentric with said extension, a double-seated sleeve valve slidably mounted in said extension and engaging said valve seat to close said inlet, resilient means for closing said valve, fluid pressure actuated means for opening said valve, said valve being constructed and arranged to form when in open position a steam passage through the valve and a second annular steam passage between the valve and the extension of said housing.

14. In an exhaust steam injector, the combination with a housing having a cylindrical extension terminating in an exhaust steam inlet; of a valve member located in said housing adjacent said inlet, said member comprising a pair of spaced annular valve seats located transversely of said inlet and concentric therewith, a cylinder mounted concentrically of said valve seats, a ported backing plate mounted in said inlet and having a bearing in alignment with said cylinder, a double-seated sleeve valve having a stem mounted at one end in said bearing and terminating at its opposite end in a piston slidably mounted in said cylinder, a spring mounted between said valve and said backing plate for closing said valve, and means for supplying fluid pressure to said cylinder to actuate said piston and said valve.

EMANUEL RAWSON.
